ENOS E. STOW, OF PLANTSVILLE, CONNECTICUT.

Design No. 3,462, dated April 27, 1869.

DESIGN FOR A HINGE.

The Schedule referred to in these Letters Patent and making part of the same.

To all whom it may concern:

Be it known that I, ENOS E. STOW, of Plantsville, in the county of Hartford, and State of Connecticut, have originated and designed a new Design for a Hinge, of which the following is a full, clear, and exact description, reference being had to the accompanying drawings, making a part of this specification, which drawing is a front elevation of my invention.

Each leaf of the hinge extends a short distance from the pintle and at right angles with the same.

Each side of each leaf is narrowed by curved lines to near the central screw-hole *a*, which is near the end of each leaf.

About two-thirds of a circle are then formed around the screw-hole *a*, the ends of which partial circle meet the ends of the curved lines before mentioned, which

thus completes the outlines of the leaves forming the hinge.

Immediately outside of the hub *A*, in which the pintle is secured, is a rounded ledge, *B*, running parallel with the hub *A*.

The whole of each leaf outside of the ledge *B* is bordered by a bead, *C*, while each screw-hole is bordered by a rounded ledge, *c*, the whole combined to produce a plain and neat design, which can be easily produced of cast metal.

What I claim as new, and desire to secure by Letters Patent, is—

The design for a hinge, herein shown and described.
